UNITED STATES PATENT OFFICE

EMIL SIMPSON, OF SPOONER, WISCONSIN

SIGN REFLECTOR

Application filed December 17, 1928. Serial No. 326,558.

The present invention relates to a sign reflector and has for its principal object to provide a reflector which may be used in numbers to form a word in conjunction with the sign that when light is thrown thereon such as automobile headlights or the like, the sign will be illuminated.

Another very important object of the invention resides in the provision of reflectors of this nature which are exceedingly simple in their construction, inexpensive to manufacture, strong and durable, thoroughly efficient and reliable in use, and otherwise well adapted to the purpose for which they are designed.

With the above and numerous other objects in view as will appear as the description proceeds, the invention resides in certain novel features of construction, and in the combination and arrangement of parts as will be hereinafter more fully described and claimed.

In the drawing:

Figure 1 is a front elevation of a sign embodying the features of my invention, 25 Figure 2 is a detail section therethrough taken horizontally substantially on the line 2-2 of Figure 1,

Figure 3 is a plan view of one of the reflectors,

Figure 4 is a longitudinal section therethrough,

Figure 5 is a rear elevation thereof,

Figure 6 is a front elevation thereof, and

Figure 7 is an enlarged detail section 35 through the inner or rear end thereof.

Referring to the drawing in detail it will be seen that the numeral 5 denotes the sign board which may be associated with any suitable casing structure 6 if so desired. The signboard has a plurality of openings in which are disposed my improved reflector for the purpose of forming letters, words, or other indicia.

Thus in Figure 1 I have formed by way of example, the word "Stop".

Each reflector includes a frusto-conical body 6 which tapers rearwardly very slightly in the present example and at the rear end is provided with a disk 7 and at the front end is provided with an outwardly disposed an-

nular flange 8. The frusto-conical body permits angular as well as direct rays of light to be reflected. This frusto-conical body 6 passes through the respective openings in the board 5 as will be understood and the flange 55 8 abuts the front surface of the bore.

Any suitable means may be used for anchoring the reflectors in place. The disk 7 includes a plain center *a* surrounded by an inwardly or forwardly directed annular 60 bulge *b* which in turn is surrounded by a plain ring *c*. This structure will show a bright spot in the center, a darker portion bounding the center, and a bright rim that is very attractive.

It is thought that the construction, utility and advantages of this invention will now be quite apparent to those skilled in this art without a more detailed description thereof. The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope 70 of the invention as hereinafter claimed or sacrificing any of its advantages.

Having thus described my invention, what I claim as new is:

1. A sign of the class described including a board with a plurality of openings therein arranged to form a legend, reflectors in the openings, each reflector comprising a frusto-conical body passing through the opening and having at one end an outwardly directed 90 right angled annular flange for overlapping the front surface of the board and at the other end a disk of compound contour.

2. A sign of the class described including a board with a plurality of openings therein arranged to form a legend, reflectors in the openings, each reflector comprising a frusto-conical body passing through the opening and having at one end an outwardly directed 95 right angled annular flange for overlapping 100

the front surface of the board and at the other end a disk, said disk including a plain center with an inwardly bulged circular portion circumjacent therethrough and a plain

5 ring portion about the bulged portion.

3. As a new article of manufacture, a reflector of the class described including a tubular body with a disk at one end thereof, said disk including a plain center with an
10 annular inwardly directed bulge portion thereabout and a plain ring portion about the bulge portion, said tubular body tapering toward the disk end thereof, the other end thereof being formed with an outwardly
15 directed annular flange.

In testimony whereof I affix my signature.

EMIL SIMPSON.
